UNITED STATES PATENT OFFICE

OSTILIO CICCARELLI, OF BRISTOL, CONNECTICUT, ASSIGNOR TO THE E. INGRAHAM COMPANY, OF BRISTOL, CONNECTICUT, A CORPORATION

DESIGN FOR A RADIOCABINET

Application filed January 14, 1933. Serial No. 46,834. Term of patent 3½ years.

To all whom it may concern:

Be it known that I, OSTILIO CICCARELLI, a citizen of the United States, residing at Bristol, in the county of Hartford and State of Connecticut, have invented a new, original, and ornamental Design for a Radiocabinet, of which the following is a specification, reference being had to the accompanying drawing, forming part thereof.

The figure is a perspective view showing my new design.

The parts other than the front panel constitute the dominant features of the design.

The far end of the cabinet is the same as the near end shown in the drawing.

I claim:

The ornamental design for a radiocabinet substantially as shown and described.

OSTILIO CICCARELLI.
